INTERMITTENT INDUCTIVE SPEED CONTROL SYSTEM FOR RAILROADS

J Donald Hughson, Rochester, and Chester Friend Stafford, Spencerport, N. Y., assignors to General Railway Signal Company, Rochester, N. Y.

Application August 2, 1952, Serial No. 302,302

9 Claims. (Cl. 246—63)

This invention relates to an intermittent inductive train control system, and more particularly pertains to a system wherein any one of a number of different speed limits may be imposed upon moving trains by the inductive transfer to appropriate train-carried equipment of respectively different controlling influences from fixed wayside locations.

In some prior intermittent inductive train control systems, a controlling influence is made effective on a train as it passes each wayside signal location only when traffic conditions ahead require that the signal display a restrictive indication. To avert an automatic penalty brake application in response to this controlling influence, it is required in these prior systems that the engineer acknowledge his observance of the restrictive signal by performing a prescribed manual act as he passes such signal. In this way, alertness of the engineer to the wayside signals is required. But in these systems, the engineer is not forced to heed the restrictive signal indication after acknowledging it, since he may operate the train at any speed he chooses.

In these prior systems, it has not been feasible to impose a control with a corresponding speed limit upon a train as it passes a signal location and have this control remain steadily effective until the train reaches the next wayside signal location. The reason is that such a system requires more than one kind of control from a wayside signal location so that a previously imposed restrictive control can be removed when traffic conditions warrant; and such a plurality of controls from a fixed wayside location to passing trains has not been available in a safe and reliable organization.

It is proposed according to this invention to provide an intermittent inductive train control system in which a plurality of different controls are inductively transferred or transmitted to appropriate apparatus on passing trains from each wayside location so that restrictive controls are selectively applied and removed as required. In this way, a particular speed limit is imposed with each different control; and, through the cooperation of speed governor equipment on the train, the system is so organized as to cause the brakes to be automatically applied whenever the then effective speed limit is violated. Thus, the system may actually be termed an intermittent inductive speed control system.

Described briefly, the train control system of this invention comprises both wayside apparatus and train-carried apparatus with the various controls transferred inductively from each wayside location to passing vehicles. The wayside apparatus includes an inductor having a control winding which may be selectively open-circuited or energized with direct current of one polarity or the other dependent upon whether a stop, caution or clear control is to be effective upon the train.

The train-carried apparatus comprises a receiver which moves through an inductive coupling relationship with the wayside inductor during train movement. The receiver has a core structure upon which is mounted a primary winding and a secondary winding. The primary

2

winding is normally energized with direct current so as to magnetize the core structure. Thus, the secondary winding is magnetically coupled to the primary winding through the receiver core structure. Distinctive changes occur in the flux of the receiver's magnetic circuit as the receiver and inductor pass through an inductive coupling relationship in accordance with whether the control winding on the inductor is open-circuited or energized with one polarity or the other. These distinctive flux changes result in correspondingly distinctive changes of current in a secondary circuit which includes the secondary winding of the receiver. These distinctive current changes that occur in the secondary circuit of the receiver cause certain relays in the train-carried apparatus to be controlled to respectively different conditions which are used to impose different speed limits.

The control that is inductively transmitted by a wayside inductor to passing vehicles when the control winding of the inductor is open-circuited, is the most restrictive control and requires that the train move at the slowest of several established speed limits. When the control winding of the inductor is energized with direct current of one particular polarity a less restrictive or caution control is transmitted to the vehicles; whereas, when the control winding of the inductor is energized with the opposite polarity a still less restrictive or clearing control is transmitted to passing vehicles. In this way, the system is organized on the fail safe principle. If, for example, a train is travelling at the permitted high speed, and traffic conditions ahead become such that it should receive a medium speed control influence upon passing the next wayside inductor, such wayside inductor has its control winding energized with said particular polarity of direct current. However, if such energization of the control winding is not established because of some circuit failure, the control winding becomes open-circuited and the inductor then transmits the most restrictive control influence to the passing train.

With such an organization where the control winding of the wayside inductor is selectively open-circuited or energized with one polarity or the other, it may happen that a circuit is completed to energize the control winding but due to a power failure the winding is in effect short-circuited. Since an inductor with a short-circuited winding is ineffective to transmit a controlling influence to the train-carried apparatus, an unsafe condition would thus arise if traffic conditions were such as to require the transmission of a caution control. However, the wayside apparatus according to this invention is so organized as to eliminate this unsafe condition by causing the control winding of an inductor to become open-circuited if the energization of the wayside inductor for either polarity drops below a certain prescribed level. If such a condition occurs, then the wayside inductor becomes effective to transmit the most restrictive control to the train-carried apparatus of a passing train.

The system of the present invention may also be organized to require that the engineer operate an acknowledging contactor each time his train passes a wayside inductor immediately in advance of a signal displaying a stop or caution control. In addition, the apparatus is organized so that the engineer is required to operate his acknowledging contactor when his train passes the wayside inductor immediately in advance of the first clear signal following the operation of the train under previously received restrictive controls. However, means is provided so that after a train has received the first clear control, it may receive successive clear controls without requiring the engineer to actuate his acknowledging contactor. This arrangement is provided to give the utmost protection to the system by avoiding the possibility of a train-carried receiver being affected falsely from some

extraneous source to give a clearing control while the train is being operated under a restrictive control previously received.

In view of the above considerations, one object of the present invention is to provide an intermittent inductive train control system in which any one of a plurality of controls can be safely and reliably transmitted from a wayside inductor to a receiver of a passing train.

Another object of the present invention is to provide the plurality of controls for such an intermittent inductive train control system by selectively opening the control winding of an inductor or energizing it with positive or negative direct current in such a way that the failure of the source of energy cannot result in the transmission of a less restrictive control.

Another object of this invention is to provide an intermittent inductive train control system in which the plurality of controls may be transmitted to a passing train from each of a plurality of successive wayside locations, with the train-carried receiving apparatus so acting in co-operation with a speed governor on the train as to impose predetermined speed limits on the train as it passes successive wayside locations which speed limits are maintained until the train passes a successive wayside location transmitting a different control.

A further object of the invention is to so organize the train-carried apparatus that the engineer is required to acknowledge the signal at each wayside location for the reception of all controls except the reception of successive clear or high speed controls. This will require that the engineer acknowledge whenever the train passes a signal location with a wayside inductor controlled to a restrictive condition and also will require that the engineer acknowledge when the train passes the first wayside location where the inductor is caused to give a clear or high speed control.

Other objects, purposes, and characteristic features of this invention will in part be obvious from the accompanying drawings and in part pointed out as the description of the invention progresses.

In describing this invention in detail, reference is made to the accompanying drawings in which like reference characters designate corresponding parts throughout the various views, and in which:

Fig. 1 is a circuit diagram illustrating in detail one embodiment of the vehicle-carried equipment of this invention;

Fig. 2 diagrammatically shows one way in which the wayside inductors may be selectively controlled in a line wire block signalling system;

Figs. 3, 4, and 5 illustrate respectively the different effects produced in the receiver secondary winding as the wayside inductor is respectively open-circuited or energized with one polarity or the other;

Fig. 6 shows a portion of the circuit of Fig. 1, particularly that portion involving the receiver secondary windings and the relays directly controlled by it; and

Figs. 7, 8, 9, and 10 are timing charts which indicate the sequence of relay operations in response to the different received controls.

To simplify the illustration and facilitate in the explanation of this invention, the various parts and circuits are shown diagrammatically and certain conventional illustrations are used. The various relays and their contacts are illustrated in a conventional manner. The symbols (+) and (-) are used to indicate connections to the opposite terminals of a battery or other source of electric current instead of showing all of the connections to these terminals.

The detailed circuit of Fig. 1 also includes, in addition to the train-carried equipment, a diagrammatic view of a wayside inductor IND. The detailed structure of a typical wayside inductor of the kind contemplated to be used in this invention may be as shown in the patent to C. S. Bushnell, No. 1,706,839, dated March 26, 1929. This

inductor, is provided with a winding CW as shown in Fig. 1, and this winding may be controlled by the wayside signalling system in the manner shown in Fig. 2.

Briefly, the wayside circuit organization of Fig. 2 includes a stretch of track divided into a plurality of track sections such as the track section 2T each having a track relay TR connected across the rails at the entrance end with a track battery TB connected across the rails at the exit end through a limiting resistor LR. An inductor IND is shown located just ahead of the entrance to each track section, and an auxiliary inductor 87 is located at approximately braking distance for medium speeds ahead of each regular inductor IND.

The inductors governing the movement of trains into any track section are controlled by a home-distant relay HD such as the relay 3HD. This relay is of the polar-retained neutral type having both polar and neutral contacts. When the winding of this relay is energized with either polarity of direct current, the neutral front contacts are closed, whereas the polar contacts are operable to either right or left-hand positions depending upon the polarity of energization applied to the winding.

The circuit organization for controlling the control winding CW of each inductor includes contacts of the associated HD relay, and also a check relay CK. An approach relay such as relay 3A indicates by its dropping away the entrance of trains into the track section 2T. A slow release repeater relay of this approach relay, such as the repeater relay 3AP, together with the check relay CK provides means for causing the control winding CW to become open-circuited if the required level of energization is not maintained as will later be explained. The wayside signals such as the signal S3 are shown diagrammatically with their control being dependent upon the approach relay A and upon the actuated condition of the associated HD relay.

Although the wayside circuit organization and in particular the manner of control of the control winding CW of the inductors will later be described in greater detail, it may be briefly stated that the circuits associated with the control of the winding CW cause this winding to be open-circuited when traffic conditions warrant transferring the most restrictive control to passing vehicles; energization of one particular polarity is used when a clearing control is to be inductively transferred, and of the opposite polarity when a medium speed or caution control is to be transferred.

The train-carried receiver REC is shown diagrammatically in Fig. 1. The receiver is mounted upon the locomotive or tender in such a manner that it passes through a relatively close inductive coupling relationship with the wayside inductor IND. As indicated by the direction of the arrow shown above the receiver, the assumed direction of motion of the receiver relative to the stationary wayside inductor is from left to right. In this Fig. 1, the relative positions of receiver and inductor are shown as those occurring at the instant when they are directly opposite each other.

The train-carried receiver REC is provided with both a primary winding and a secondary winding which are magnetically coupled to each other through the core structure of the receiver. In one specific embodiment of this invention, the receiver used was of the kind shown in the Patent 1,733,982 to C. S. Bushnell, dated October 29, 1929. Merely by way of illustration, the secondary and primary windings are so situated on the receiver with respect to the normal direction of travel of the receiver in the embodiment of the invention shown in Fig. 1 that the primary winding is towards the front of the vehicle and becomes inductively coupled with the wayside inductor before the secondary winding. The principles of the invention apply equally well when the secondary rather than the primary winding is located towards the front of the receiver. The effect produced with

this latter arrangement of receiver windings will later be described.

The primary winding of the receiver is energized with direct current. The ampere turns of the magnetization applied to the receiver by the field of the primary winding are sufficient to establish a relatively strong magnetic field. In the embodiment of the invention shown in Fig. 1, the polarity of energization of the receiver primary was selected to cause the pole of the receiver bearing the primary winding to be a south pole, so that the other leg of the receiver bearing the secondary winding then became a north pole. This particular selection of polarities is mentioned merely for purposes of illustration; the opposite polarities may as well be used.

The train-carried apparatus also includes an electro-pneumatic valve EPV which is diagrammatically illustrated in Fig. 1. When electrical energy is applied to this valve, the control of the air brakes on the train is entirely under the direction of the engineer. If this electrical energy supplied to the EPV valve is removed, the valve causes the air pressure for the brakes to be immediately reduced with the effect of causing a service brake application. One valve EPV of this kind is shown in the Patent No. 1,649,444 to C. S. Bushnell, dated November 15, 1927.

A speed governor SG is also shown diagrammatically in Fig. 1. Although illustrated in the drawing as being a speed governor of the centrifugal type, other types of speed governor may also be used without departing from the scope of the invention. One type of speed governor that may be used is illustrated in detail in the Patent No. 2,457,748 to H. B. Taylor, dated December 28, 1949. As indicated in Fig. 1 the various governor contacts open at different train speeds for effecting different control of the train-carried equipment at the different train speeds.

The acknowledge contactor ACK is illustrated diagrammatically in Fig. 1 as controlling a plurality of contacts. This contactor also has associated with it a timing device which controls the contact 30. If the acknowledge contactor is continuously actuated for a relatively long time interval as, for example, in excess of fifteen seconds, then the timing device which is initiated into operation when the acknowledge contactor ACK is first operated, causes this contact to open. The circuit to the valve EPV is then opened and an automatic brake application occurs. This action discourages any attempt to hold the acknowledge contactor actuated in order to eliminate the need for acknowledging each restrictive signal indication. In one particular embodiment of the invention, the acknowledge contactor ACK which was used was of the type shown in the Patent No. 1,725,729 to C. S. Bushnell, dated August 20, 1929.

The suppression contactor SC shown in Fig. 1 prevents deenergization of the valve EPV under certain conditions even though the timing relay TD has dropped away. If, for example, a restrictive control becomes effective on the train-carried equipment and the train is at that time moving at a speed in excess of the speed limit corresponding to that control, the timing relay TD becomes deenergized as will later be more fully described. The opening of front contact 31 of relay TD ordinarily results in the deenergization of the valve EPV so that an automatic brake application follows. But this action can be circumvented by the engineer's making a service brake application prior to the dropping away of relay TD. A service brake application causes an increase in pressure at the inlet pipe 32 of the brake suppression valve BSV so that the contacts 33 become closed through the contact 34 on the cylinder of the brake suppression valve. In one specific embodiment of this invention, the brake suppression valve BSV was of the type illustrated in the patent to C. S. Bushnell, No. 1,757,410, dated May 6, 1930.

The train-carried equipment also comprises a number

of electro-magnetic relays. Among these are the negative-responsive and positive-responsive relays NR and PR which are distinctively controlled in accordance with the variations of current taking place in the receiver secondary winding through the inductive effects of the wayside inductors. The relay R3 is a penalty relay; the dropping away of this relay may occur, for example, through failure to properly acknowledge restrictive signal indications. When this relay drops away the valve EPV becomes deenergized and an automatic brake application follows. The train-carried equipment can then be reset to its normal condition only by bringing the train to a very slow speed.

The slow release relay R5 is ordinarily dropped away whenever the train passes an inductor at a restrictive signal location. During the time that this relay R5 is dropped away, the acknowledge contactor ACK is required to be operated in order to prevent dropping away of the penalty relay R3. The relay NRP is a repeater of the relay NR and one of its functions is to cause the receiver secondary circuit to be closed after the circuit has been opened by the dropping away of relay NR. The medium speed and high speed relays MS and HS respectively are selectively actuated in accordance with whether a medium speed or high speed control is received at a wayside inductor location. These relays store such a control only momentarily; such momentarily stored control is transferred to a corresponding repeater relay MSP or HSP depending upon the control received. These latter relays are provided with stick circuits which hold a control received at one wayside inductor location until a different control is received at a following inductor location.

The timing relay TD is a slow release relay as indicated by the heavy base line for the symbol representing this relay. This relay TD is ordinarily required to be in a picked up condition in order for the valve EPV to be energized. The energization of this relay TD is, in turn, dependent upon the train speed being kept below the then effective speed limit as established by the control received from the wayside inductor last passed by the train.

The condition of the various relays included in the vehicle-carried apparatus are those they assume when the train-carried apparatus has been properly "reset," no controlling influence has yet been received from a wayside inductor, and the train is moving below its most restrictive speed. The manner in which the various relays and contacts are closed to assume these conditions upon resetting will now be described.

Prior to the resetting operation about to be described, the various relays and devices remain in deenergized conditions. The reason that all of the relays and devices (see Fig. 1) remain deenergized is that they receive electrical energy over wire 10, and this wire is normally energized from (+) and through front contact 11 of relay R5 and front contact 12 of relay R3. But with relay R3 along with all the other relays initially deenergized, the front contact 12 of this relay R3 is open so that electrical energy is not applied to the wire 10. Under this condition, the electro-pneumatic valve EPV is also deenergized and, as will later be described, the brakes on the train cannot be released until this valve becomes energized.

With the train at a standstill, contact 13 of the speed governor SG is closed as indicated in Fig. 1. By actuating the acknowledge contactor ACK at this time, energy is applied from (+), through the whistle valve WV, back contact 14 of the acknowledge contactor ACK, closed contact 13 of the speed governor SG, back contact 15 of the acknowledge contactor ACK to the wire 10. With wire 10 now energized, a circuit is established through the winding of relay R3, the ballast lamp BL and the primary winding PR1 on the receiver REC, to (-). This circuit causes the relay R3 to pick up and

also energizes the receiver primary winding PR1. The ballast lamp BL is included in series with the primary winding to keep the energization of this winding at a fairly constant level despite variations in the value of supply voltage that may occur. In this way, the degree of magnetization of the receiver is held substantially constant.

The electrical energy appearing on wire 10 as a result of actuation of the acknowledge contactor ACK during the resetting operation also causes current to flow from wire 10 through back contact 16 of relay NRP, the winding of relay PR, the secondary winding SEC of the receiver REC, the winding of relay NR, the ballast lamp BL, and the primary winding PR1 of the receiver to (-). Since the resistance of relays NR and PR is fairly high, the amplitude of current through relays NR and PR and the secondary winding is maintained at a fairly low value as compared to that existing in the receiver primary winding. Therefore, the number of ampere turns contributed by the energization of the secondary winding to the magnetic circuit of the receiver is very small as compared to that furnished by the energized primary winding.

The normal current level through the receiver secondary winding and the operating characteristics of the relays PR and NR are so selected in relation to each other that the normal receiver secondary current is greater than the pick-up current level for relay NR but is below the drop away current level for the relay PR. Normally, therefore, the relay NR is picked up by the circuit just described while the relay PR remains dropped away.

With relay NR now picked up, a circuit is completed to energize the front repeater relay NRP of relay NR. This circuit extends from the now energized wire 10, through front contact 17 of relay NR, wire 18, back contact 19 of the acknowledge contactor ACK, back contact 20 of relay R5, back contact 21 of relay HSP, back contact 22 of relay MSP, and the winding of relay NRP to (-). As soon as this relay NRP is picked up, it is held up through a stick circuit which includes the front contact 23 of this relay.

When relay NRP is picked up, the opening of its back contact 16 opens the pick up circuit for relay NR but this relay NR and the receiver secondary winding remain energized through the stick circuit for relay NR which includes front contact 24 of this relay NR. The picking up of relay NRP also completes a circuit for the energization of relay R5. This circuit extends from wire 10 and includes the front contact 25 of relay NRP and the winding of relay R5 to (-). Now with relays R3 and R5 both energized, the acknowledge contactor ACK can be released as electrical energy is now applied to wire 10 from (+), through front contact 11 of relay R5 and front contact 12 of relay R3.

When energy first appears on the wire 10 during the resetting operation, a circuit is completed to energize the slow release timing relay TD. This circuit is established from the wire 10, through contact 26 of the speed governor SG, back contacts 27 and 28 of relays HSP and MSP, and the winding of the relay TD to (-). As soon as relay TD picks up, a circuit is completed from wire 10 and including the normally closed contact 30 of the acknowledge contactor ACK and front contact 31 of relay TD to energize the valve EPV. With the valve EPV energized, the engineer is able to release the brakes and put the train into motion. With the resetting operation now completed, the various relays and devices are in the condition illustrated in Fig. 1.

INDUCTIVE RELATIONSHIPS

Prior to giving a detailed description of the manner of operation of this invention, it is believed that the description of the invention will best be facilitated by describing the different effects produced in the receiver secondary circuit as the receiver passes wayside inductors controlled to different conditions. These different effects on the

receiver secondary current are illustrated graphically in the Figs. 3, 4, and 5.

The winding of a typical wayside inductor is illustrated in these Figs. 3-5 as being controlled through the contacts of a HD relay as already briefly explained. This manner of control is shown in greater detail in Fig. 2. The graphical illustrations of Figs. 3-5 are not intended to show exactly the way in which the receiver secondary current is varied; they represent the current variations in only an approximate manner. Fig. 6 shows a portion of the circuit of Fig. 1, particularly illustrating the circuit relationships involved in the control of the relays NR and PR by the inductive action affecting the secondary winding SEC.

When the vehicle-carried receiver passes through an inductive coupling relationship with an inductor having its control winding open-circuited as in Fig. 3, the current in the secondary winding of the receiver experiences a substantial decrease. The normal level of receiver secondary current is at some value which is above the drop away current level for the relay NR but is below the pick-up current level for the relay PR as shown in Fig. 3. This normal current value is also above the pick-up current level for relay NR which is somewhat above the drop away current level shown for this relay. As the receiver passes the open-circuited inductor, the secondary current in the receiver is momentarily decreased to a level below the drop away current level for the NR relay. As described, the NR relay (see Fig. 6) is maintained normally energized through a stick circuit which includes the front contact 24 of this relay. Therefore, even a momentary reduction of the energizing current for this relay sufficient to cause the front contact 24 to open for an instant results in the complete deenergization and dropping away of this relay. Upon the dropping away of relay R1 the circuit for the secondary winding of the receiver is opened for a brief interval. The dropping away of relay NR results in the deenergization of relay NRP so that this relay NRP quickly drops away, and, by the closing of its back contact, causes the receiver secondary circuit to become closed. The effect on the receiver secondary current caused by the momentary opening of the secondary circuit is not shown in Figs. 3-5.

In Fig. 4, the relay HD is shown energized so as to cause the front contact 35 to be closed, and the polarity of the energization causes the polar contacts 36 and 37 of this relay to be in their left-hand positions. The resulting polarity of energization of the control winding CW for the wayside inductor IND is assumed to so magnetize the wayside inductor that its polarity "aids" the magnetic field of the receiver in that, with unlike poles opposite each other, the normal magnitude of receiver flux is increased. Under these circumstances, the secondary current level is first reduced to a level that is below the drop away current level for the NR relay so that this relay drops away. Immediately afterwards, the secondary current level rises momentarily above its normal value to a level that causes the picking up of relay PR. These current variations are illustrated roughly in Fig. 4.

The effect on the receiver secondary winding when the control winding of the inductor is energized with the opposite polarity from that of Fig. 4 is shown in Fig. 5. Here the relay HD is shown energized so that front contact 35 is closed, and the polarity of this energization causes the polar contacts 36 and 37 to be in their right-hand positions. This polarity of energization results in a magnetic field for the receiver opposite that shown in Fig. 4. This magnetic field is designated as an "opposing" field since, with like poles opposite each other when receiver and inductor are directly opposite, the normal receiver flux is decreased. In response to these conditions the receiver secondary current varies approximately as shown in this Fig. 5 as the receiver passes

the inductor in that the current first rises above its normal value to a value sufficient to cause the relay PR to pick up and then decreases to a value below its normal value so that the NR relay is dropped away.

The distinctively different effects produced on the receiver secondary current in response to the differently controlled conditions of the control winding for the wayside inductor are demonstrated in an approximate manner by these Figs. 2, 3, and 4. To summarize, an inductor with its control winding CW open-circuited produces substantially only a current decrease in the receiver secondary winding so that the only effect on the associated relays is to cause relay NR to drop away. Under these circumstances the inductor is not effective to cause operation of the PR relay.

When the inductor's control winding CW is energized with a polarity to cause its magnetic field to "aid" that of the receiver when the receiver and inductor are opposite each other, the receiver current is first reduced and then increased. The sequence of relay operations produced by this change in receiver secondary current is first a dropping away of the NR relay followed by the picking up of the PR relay.

Upon reversal of the polarity of magnetization of the inductor by reversing the polarity of the current applied to the control winding CW, the effect produced on the receiver secondary current is substantially also reversed. Instead of a decrease of current followed by an increase as illustrated in Fig. 3, the current now first increases and then decreases. This reversal also reverses the sequence of operation of the relays NR and PR in that the first occurring current increase causes relay PR to pick up and then the following current decrease causes relay NR to drop away.

As previously mentioned, the receiver REC may be constructed so that the secondary rather than the primary winding is towards the front of the vehicle. Then during normal forward movement of the vehicle, the waveform of receiver secondary current caused by wayside inductors having their control winding energized is substantially opposite that shown in Figs. 4 and 5. In other words, a receiver having its secondary winding toward the front but with relative polarities of magnetization unchanged and becoming inductively coupled with a wayside inductor controlled to supply an "aiding" magnetic field as in Fig. 4 experiences a current change in its secondary winding that comprises first a current increase followed by a current decrease as shown in Fig. 5 rather than the opposite condition illustrated in Fig. 4. Similarly, a receiver in this condition and becoming inductively coupled with an inductor energized to have an "opposing" magnetic field as in Fig. 5 experiences a secondary current change approximately like that shown in Fig. 4. The reason for this effect is believed to be caused by the fact that the circuit associated with the secondary winding of the receiver is of high impedance; whereas, the circuit associated with the primary winding is of considerably lower impedance. The coupling of the leg of the receiver bearing the secondary winding with the inductor thus is believed to produce a substantially greater effect on secondary current than when the leg bearing the primary winding is so inductively coupled. This dissymmetry with respect to the two legs of the receiver structure causes the effect produced in the receiver secondary circuit to be dependent upon whether the leg bearing the primary or the secondary winding first becomes inductively coupled with the wayside inductor.

The sequence of relay operations of the relays NR and PR that occurs as the train-carried receiver passes a wayside inductor determines the nature of the received control. The manner in which this sequence of relay operations is effective to impose different controls with correspondingly different speed limits will be fully described. Briefly, however, in the embodiment of the in-

vention shewn in Fig. 1, if the relay NR alone is actuated, the most restrictive control and lowest speed limit is put into effect; if the relay NR is first dropped away followed by the picking up of the relay PR, an intermediate speed limit is established; and if the PR relay first picks up followed by the dropping away of relay NR, the maximum speed limit becomes permissible.

In other words, the differently controlled conditions of the wayside inductor shown in Figs. 4 and 5 are utilized for transferring caution and clear controls respectively to the train-carried equipment as indicated in these drawings. It should be understood, however, that the opposite selection of polarities for the control winding CW may also be used. That is, an inductor energized for an "aiding" field may as well be used to give a clear control as to give a caution control. In that event, an inductor having its control winding energized for an "opposing" field then becomes effective to give a caution control.

20

OPERATION

Normal condition

The normal condition of most of the train-carried equipment has already been described. The relays MS, HS, MSP, and HSP initially remain deenergized when the vehicle-carried equipment is first put into its normal operating condition by the resetting operation previously described. With both relays HSP and MSP deenergized, the train speed should not be allowed to exceed the predetermined low speed limit because the dropped away condition of the relays HSP and MSP causes relay TD to be energized through the low speed contact 26 of the speed governor. Increasing the speed above this low speed limit causes this contact 26 to open and relay TD to be deenergized with a resulting deenergization of the valve EPV. This action causes the brakes to be automatically applied unless a service brake application is immediately made so as to close the suppression contactor SC.

Receiving most restrictive or "stop and proceed" control

When the vehicle-carried receiver REC passes through an inductive coupling relationship with a wayside inductor that is open-circuited, a momentary decrease of the normal current level through the secondary winding of the receiver results. This variation in receiver secondary current is illustrated graphically in an approximate manner in Fig. 3. As already described, this current decrease causes the relay NR to drop away but does not affect relay PR since the level of current through the relay PR does not rise above the pick up level of current required for this relay.

With relay NR deenergized, its front contact 24 opens to thereby open the receiver secondary circuit. Relay NRP then drops away as indicated in Fig. 7 because of the opening of front contact 17 of relay NR. Relay NRP drops away quickly thereby again closing the secondary circuit at back contact 16 of relay NRP, and relay NR picks up as the secondary current increases toward its normal value. Relay NRP cannot again become picked up at this time because of its open front contact 23.

The dropping away of relay NRP also opens front contact 25 so that relay R5 is deenergized (see Fig. 7). The resulting release of the relay R5 after a short interval due to its slow drop away characteristics would ordinarily result in the removal of energy from wire 10. But this can be circumvented by timely operation of the acknowledge contactor ACK so as to close its back contact 14 and thereby maintain the wire 10 energized.

The dropping away of relay R5 also causes front contacts 40 and 41 of this relay to open the stick circuits for both relays HSP and MSP. With either relay HSP or MSP in a picked up condition, the caution or clear control is then in force as will be more fully explained.

The dropping away of relay R5 ensures that both of these

70

The sequence of relay operations of the relays NR and PR that occurs as the train-carried receiver passes a wayside inductor determines the nature of the received control. The manner in which this sequence of relay operations is effective to impose different controls with correspondingly different speed limits will be fully described. Briefly, however, in the embodiment of the in-

relays HSP and MSP are released so that the most restrictive control comes into effect.

When back contact 20 of relay R5 closes and assuming that the acknowledge contactor ACK has been actuated to close its back contactor 19, the pick-up circuit for relay NRP previously described is again established so that this relay picks up. The pick-up circuit for relay NR is thereby opened again by the opening of back contact 16 of relay NRP so that the receiver secondary circuit is once more closed only through the front stick contact 24 of relay NR. Also, with relay NRP now again picked up, its front contact is closed to energize relay R5. When relay R5 picks up and closes its front contact 11, energy is once more applied through this contact to wire 10 so that the acknowledge contactor ACK can be released.

The circuit conditions established when the receiver passes a wayside inductor that has its control winding open-circuited in this way result in the relays HSP and MSP being dropped away. With both back contacts 27 and 28 of the relays HSP and MSP closed, the energizing circuit for relay TD is required to be completed through contact 26 of the speed governor SG. The train speed should not exceed the selected speed at which this governor contact opens as otherwise the relay TD becomes deenergized, requiring that the brakes be applied to restore the speed to the proper level under penalty of an automatic brake application.

Throughout the time that the train-carried apparatus is effected by the wayside inductor, the acknowledge contactor ACK is required to be actuated so that wire 10 will remain energized through back contact 14 of this contactor during the interval that the relay R5 is dropped away. Otherwise, the penalty relay R3 is dropped away, and, if this happens, subsequent actuation of the contactor ACK will not suffice to reenergize wire 10 because of the open front contact 12 of relay R3. The valve EPV then becomes deenergized and an automatic brake application follows. The train-carried equipment can then be restored to its normal operating condition only through the resetting operation already described. This can take place only when the train speed has been sufficiently reduced to allow contact 13 of the speed governor to close. This requirement of a very low train speed before resetting can occur is the penalty inflicted for failure to acknowledge the restrictive signal.

The pneumatic train brake system may be organized so that the brakes cannot immediately be released following an automatic brake application until a certain time has elapsed even after the train-carried equipment such as shown in Fig. 1 has been restored to its normal condition and the valve EPV again energized. The means for such control may take the form illustrated in Pat. No. 1,855,595 to C. S. Bushnell, dated April 26, 1932. When the brakes are applied by the engineer, they can quickly be released by him. It is to his interest, therefore, to prevent an automatic brake application. Otherwise the brakes remain effective for a time even after the train speed has been reduced to the level where closure of speed governor contact 13 allows resetting to occur so that the train is, in practice, usually brought to a full stop.

Reception of caution or medium speed control

When the vehicle-carried receiver passes through an inductive coupling relationship with the wayside inductor under the conditions shown in Fig. 4, the current in the secondary winding of the receiver is first momentarily decreased below its normal level and then increased above its normal level. The first-occurring current decrease causes relay NR to drop away. When front contact 17 of this relay opens, relay NRP drops away (see Fig. 8). The closure of back contact 16 of relay NRP shunts the now open front contact 24 of relay NR to thereby close the receiver secondary current so that the

following current increase will be effective upon the relay PR.

The dropping away of relay NRP opens the energizing circuit for relay R5 at front contact 25 of relay NRP. The slow release characteristics of relay R5 are selected so that this relay does not drop away upon its deenergization until after the current increase in the receiver secondary circuit has been effective to cause the momentary picking up of relay PR even for the lowest train speeds when there may be a substantial interval after relay NR drops away before relay PR picks up.

When relay PR does pick up momentarily in response to the current increase, a circuit is completed from the energized wire 10, through front contact 42 of relay PR and back contact 43 of relay NRP to energize the relay MS. Relay PR remains picked up only for a short time, but during this interval the circuit described causes energy to be applied to both the winding of relay MS and to the capacitor 44 which is in series with the current limiting resistor 45 across the winding of relay MS. This capacitor 44 receives a substantial charge during the short time that the relay PR is picked up.

When the train is operating at high speeds, the duration of the positive current pulse is shorter than at slower train speeds; but it has been found that even under conditions where relay PR is picked up only for a very brief interval, the capacitor 44 receives a substantial charge while front contact 42 of relay PR is closed. Even though front contact 42 may open before relay MS picks up, the subsequent discharge of capacitor 44 through the winding of relay MS causes this relay to pick up. After relay MS has once closed its front contact 46, the capacitor 47, which was charged through back contact 46 when relay MS was in its dropped away condition, discharges through the upper winding of relay MS and holds this relay picked up for a time.

When front contact 48 of relay MS closes, wire 10 which is connected to the right-hand terminal of the winding of relay PR is connected to wire 49 which is connected to the left-hand terminal of the same winding. In this way, one result of the picking up of relay MS is that it results in the short-circuiting of the winding of relay PR and ensures that this relay is restored to its original dropped away condition.

After relay NRP has been dropped away for some time and the momentary picking up of relay PR has resulted in the energization of relay MS, relay R5 drops away (see Fig. 8). In doing so, the front contacts 40 and 41 of this relay open the stick circuits for the relays HSP and MSP. In the event that either of these relays was picked up as the vehicle passed the preceding inductor, such relay is now once more dropped away to clear out the previously received control and to allow the new control to become effective.

The dropping away of relay R5 again opens the normal energizing circuit for wire 10. For this reason, the engineer is required to operate the acknowledge contactor ACK when passing a signal displaying a caution indication.

When relay R5 drops away, its back contact 20 closes. Since the acknowledge contactor ACK is now actuated and its back contact 19 closed, and since the relays HSP and MSP are now both dropped away, the pick-up circuit for relay NRP already described is once more established and this relay picks up. With the opening of back contact 16 of relay NRP, the shunt on the front contact 24 of relay NR is removed so that relay NR is again maintained energized through its stick circuit. Also, energy is now applied from wire 10, through the now closed front contact 16 of relay NRP and through the still closed front contact 50 of relay MS to energize the winding of relay MSP as indicated in Fig. 8.

At the same time, the closure of front contact 25 of relay NRP causes relay R5 to be picked up. Wire 10 is then once more energized through front contact 11 of this relay R5 so that the acknowledge contactor ACK need

no longer be held actuated. The closure of front contact 41 of this relay R5 also closes a stick circuit for the relay MSP. This stick circuit includes, in addition to front contact 41 of relay R5, back contact 51 of relay HSP and the front contact 52 of relay MSP.

With relay MSP picked up, the timing relay TD is now energized through front contact 28 of the relay MSP and the medium speed contact 53 of the speed governor SG. Under this condition, the train speed is required to be kept below the medium speed limit to avoid deenergization of relay TD as this may result in an automatic brake application as already described. The whole cycle of relay operations involved in imposing a caution control with an intermediate speed limit on the train is thus completed. Summarized, the action of the NR and PR relays results in the dropping away of relay NRP followed by the deenergization of relay R5 which remains picked up for a time. Relay MS is picked up when relay PR is momentarily actuated. Actuation of the acknowledge contactor ACK is required to prevent dropping away of the penalty relay R3 because relay R5 soon drops away. The dropping away of relay R5 opens the stick circuits to relay HSP and MSP so that any previously received control less restrictive than a stop control is removed, and this is followed by the picking up of relay NRP. With relay NRP picked up, relay R5 is picked up as is also relay MSP which latter relay is maintained picked up by a stick circuit which can now again be established because relay R5 is picked up. The control of relay TD is now governed through the medium speed contact of the speed governor SG so that the medium speed limit must be adhered to.

Reception of clear control (first)

When the vehicle passes a wayside signal location and that signal is displaying a clear or proceed indication, the wayside inductor according to the present embodiment of the invention has its control winding energized to produce the conditions outlined in Fig. 5. As described in connection with this Fig. 5, the effect produced on the current in the receiver secondary winding as the receiver passes the wayside inductor is an increase of the current above its normal level for a brief time followed by a negative current pulse which causes the current to drop below its normal value. The result is a momentary picking up of the relay PR followed by a dropping away of the relay NR.

When the vehicle is operating through regions where the traffic conditions require train movement at restricted speeds, it is desirable that all possible precautions be taken to ensure that a false clearing signal will not be effective on the vehicle. Magnetized objects lying along the track rails might conceivably affect the receiver so as to produce a variation of current in the secondary winding which roughly approximates that obtained under the conditions of Fig. 5. If the train has been controlled to operate at some restricted speed limit, such spurious response would cause the restriction to be removed. For this reason, the vehicle-carried apparatus has been organized so that acknowledgement by the engineer is required when a clearing input is received only if the vehicle is and prior to the time of such clearing impulse has been required by a previously received control to operate at a restricted speed. Since the engineer performs the act of acknowledgement only at wayside signal locations, the possibility of receiving a spurious input which would produce a clearing effect on the vehicle is greatly reduced. But when the vehicle has been operating through clear territory and has already received a clearing control, acknowledgement by the engineer is not required as the vehicle passes successive wayside signals which display a clear or proceed indication. When considered desirable, the train-carried apparatus may be so organized that acknowledgement is not required at any clear signal.

The effect of a wayside inductor having its control winding energized to give a clearing control will first be described from the standpoint of its effect on train-carried equipment that has been operating in response to a restrictive input from a previously passed wayside inductor. If the winding of the wayside inductor previously passed were controlled to give the most restrictive control, both relays HSP and MSP would be deenergized. If the wayside inductor previously passed had its control winding energized to give an intermediate or caution control, the relay MSP would be picked up but the relay HSP would still be dropped away. These are the principal effects of the two restrictive controls on the train-carried apparatus. Under either of these conditions, the receipt of a clearing input from the wayside inductor requires that the acknowledge contactor ACK be actuated in order that the restrictive control then in effect can be removed and the vehicle allowed to operate at its maximum speed and also to avert an automatic application of the brakes.

The first effect produced on the train-carried equipment as the receiver passes the wayside inductor IND is the momentary picking up of relay PR in response to the positive current pulse. As the front contact 42 of relay PR momentarily closes, energy is applied to the winding of relay HS from wire 10 and also to its shunting capacitor 54 through the resistor 55. Relay HS picks up in response to this momentary energization and remains picked up for a time after front contact 42 of relay PR open as the charged capacitor 65 discharges through front contact 56 into the upper winding of this relay HS. The closure of front contact 57 of relay HS shunts the winding of relay PR in a manner similar to that occurring when relay MS picks up when an intermediate speed control is received so that relay PR quickly drops away.

Shortly afterward, the receiver secondary current is abruptly decreased in value below its normal current level so that relay NR drops away. With front contact 24 of relay NR open, the receiver secondary circuit is also opened. But the opening of front contact 17 of relay NR also causes relay NRP to drop away so that the receiver secondary circuit is again quickly closed at back contact 16 of relay NRP and relay NR is quickly picked up as the receiver secondary current rises to its normal value.

With relay NRP now dropped away and relay HS still picked up, assuming the acknowledge contactor ACK has been actuated as required for the clearing control to be properly received, a circuit is completed from wire 10 to energize the relay HSP. This circuit extends from wire 10 and includes back contact 58 of the contactor ACK, front contact 59 of the high speed relay HS, and back contact 60 of the relay NRP. When relay HSP picks up, a stick circuit is completed to hold this relay energized, and this stick circuit extends from wire 10, through front contact 40 of relay R5, front contact 61 of relay HSP, and through the winding of relay HSP to (-). At the same time, the picking up of the relay HSP causes a pick-up circuit to be closed for the relay NRP. This circuit extends from the wire 10 and includes front contact 62 of relay HSP, front contact 63 of relay HS and the winding of relay NRP to (-). With relay NRP picked up, the pick-up circuit for relay HSP is opened so that this relay is held energized only through its stick circuit.

The energization circuit for relay R5 is again closed by the closing of front contact 25 of relay NRP. Since the dropping away of relay NRP resulted in the picking up of relay HSP and the picking up of relay HSP, in turn, causes relay NRP to be picked up, relay R5 is deenergized for only a very short time and does not have time to be dropped away under these conditions.

If the engineer failed to acknowledge, not only would the clearing control fail to become effective by not picking up relay HSP, but the failure of relay HSP to pick up would also prevent the picking up of relay NRP.

through front contact 62 of relay HSP. Relay R5 would then drop away followed by the dropping away of relay R3 and an automatic brake application would occur. From this description it becomes clear that if the relay HSP is not in its picked up condition, the acknowledge contactor ACK must be operated as the receiver passes the wayside inductor controlled to give a clearing control in order for the pick-up circuit for relay HSP to be completed and the maximum speed limit for the vehicle to be established. In summary, the initial picking up of relay PR with relay NRP still picked up causes relay HS to be energized. When relay NR drops away and then relay NRP also, relay HSP is picked up provided that the acknowledge contactor ACK has been actuated. Relay NRP then picks up and relay HSP is maintained energized through a stick circuit.

When relay HSP picks up, the opening of its back contact 51 opens the stick circuit for relay MSP to ensure that any previously received intermediate speed control is cancelled. With relay HSP picked up and relay MSP dropped way, relay TD is energized from wire 10 through the high speed contact 64 of the speed governor SG, front contact 27 of relay HSP, and back contact 28 of relay MSP. The train speed need only be kept below the speed at which this contact 64 opens for relay TD to remain energized and an automatic brake application forestalled.

Reception of clear control (successive)

The apparatus on the vehicle is organized so that acknowledgement by the engineer is not required to receive a clearing control if the vehicle has previously been controlled to operate up to its maximum speed limit. Under these circumstances, relay HSP is in a picked up condition when the train approaches the inductor, and this condition is utilized to eliminate the need for acknowledging.

The effect on the receiver secondary circuit in response to the effect produced by an inductor controlled to give a clearing influence is a momentary current increase followed by a decrease of current. As the current increases, relay PR is momentarily picked up. A circuit is then completed from the energized wire 10, through front contact 42 of relay PR, and front contact 43 of relay NRP to energize the lower winding of relay HS. As soon as relay HS picks up, a circuit is completed from wire 10, through front contact 62 of relay HSP, front contact 63 of relay HS, and the winding of relay NRP to (—) which maintains the relay NRP energized. Even though the picking up of relay PR is but a momentary condition, the relay HS remains picked up for some time after the front contact 42 opens because of the discharge of capacitor 65 through its upper winding. With front contact 62 of the relay HS held closed for a time, relay NRP continues to receive energy over this pick up circuit.

When the subsequent negative current pulse in the receiver secondary winding causes relay NR to momentarily drop away, the stick circuit for relay NRP is opened at the open front contact 17 of relay NR. But relay NRP cannot drop away because it is maintained energized through the circuit just described. With relay NRP prevented from dropping away, the relay R5 is not deenergized so that the stick circuit for the relay HSP is not interrupted nor is energy removed from the wire 10 by the opening of front contact 11 of relay R5. For this reason, operation of the acknowledge contactor ACK is not required and the train can then continue to operate at speeds up to its maximum speed limit. When relay HS is picked up in response to the picking up of relay PR, front contact 57 of relay HS closes to shunt the winding of relay PR and front contact 24 of relay NR. One effect of this shunting action is to ensure that relay PR drops away. Another effect is to provide a circuit whereby relay NR may be picked up because under these circumstances relay NRP does not drop away so as to close the secondary circuit at back contact 16.

WAYSIDE APPARATUS

Fig. 2 illustrates the wayside signalling apparatus which controls the wayside inductors. A typical portion of track signalled by a line wire block signalling system is shown.

Each track section such as the track section 2T has connected to its rails at the exit end thereof a track battery 2TB connected in series with a current limiting variable resistor 2LR. At the entrance end of each track section a track relay TR is connected across the track rails. A home-distant relay HD is also located at the entrance end of each track section. This relay is controlled over line wires extending from the next signal location ahead. The relay HD is of the kind known commonly as a polar-retained neutral relay as previously mentioned. The polarity of the energization applied to each HD relay is determined by whether the HD relay for the track section ahead is picked up or dropped away. Assuming that the track relay 2TR is picked up because of non-occupancy of the track section 2T so that front contacts 66 and 67 of relay 2TR are closed, the relay 2HD has its polar contacts 36 and 37 actuated to their right-hand positions when the relay 3HD is picked up. But the polar contacts 36 and 37 are operated to their left-hand positions when the relay 3HD is dropped away.

At each signal location there is an approach relay such as the relay 3A at the signal S3 location. This relay is included in the line wire circuit including line wires 68 and 69 extending from this signal location to the relay 2HD at the entrance of track section 2T. The function of this relay 3A is to prevent energy from being applied to the wayside inductor IND and to the lamps of the wayside signal S3 except when there is a train actually occupying the track section 2T.

The wayside signalling apparatus shown in Fig. 2 is illustrated as being in the normal condition, i. e. the condition that it assumes when traffic conditions warrant unrestricted train movement and when there is no train in any of the track sections shown. Consequently, the track relay TR at the entrance to each track section is picked up. Also, each HD relay such as the relay 2HD is energized because of the closed front contact of the associated track relay 2TR. With each relay HD picked up, the polarity of the energy applied over the line wires to the HD relay at the next preceding signal location is such as to cause the polar contacts of such HD relay to be operated to their right-hand positions. At the same time, each approach relay such as relay 3A is picked up, and its associated repeater relay AP is also energized. The relay 3AP is energized, for example, through the front contact 70 of the relay 3A.

If a train occupies the track section 3T, the track relay 3TR is dropped away. The relay 3HD is also dropped away because of the open front contacts 71 and 72 of relay 3TR. If another following train enters the track section 2T, the track relay 2TR also drops away and because of the opening of front contacts 66 and 67 of relay 2TR, relay 2HD is deenergized. With no current flowing in the line wires 68 and 69, the approach relay 3A also becomes deenergized and drops away. A circuit is then completed through back contact 73 of relay 3A, back contact 74 of relay 3HD and lamp R of the wayside signal S3 to (—). A red aspect is thus displayed by the signal S3 to warn the approaching train in the track section 2T of the occupancy of track section 3T by another train.

Because relay 3HD is dropped away and its front contact 75 is open, a circuit cannot be completed to energize the control winding CW of the wayside inductor IND at the signal S3 location. When the train-carried receiver passes this wayside inductor, the open-circuited control winding CW will cause the most restrictive control to be inductively transmitted to the train-carried equipment.

It will now be assumed that a train is still occupying the track section 3T, that track section 2T is not occupied by any train, and that a train enters the track section 1T.

Relays 3TR and 3HD are still in their dropped away condition but relays 2TR and 2HD are now picked up. With back contacts 76 and 77 of relay 3HD closed, the polarity of the energization applied over line wires 68 and 69 to relay 2HD causes the polar contacts of this relay to be in their left-hand positions. Since track section 1T is occupied, the approach relay 2A becomes deenergized when the train first enters this track section 1T. A circuit is then completed from (+), through back contact 78 of relay 2A, front contact 79 of relay 2HD, and left-hand contact 80 of relay 2HD, and through the lamp Y of the wayside signal S2 to (-). In this way, a caution indication is displayed by the wayside signal 2.

The closure of back contact 81 of relay 2A completes a circuit for energizing the control winding CW of the wayside inductor IND at this location. This circuit extends from (+), and includes left-hand contact 37 of relay 2HD, the winding of relay 2CK, front contact 82 of relay 2AP, back contact 81 of relay 2A, the control winding CW of wayside inductor IND, and the left-hand contact 36 of relay 2HD to (-). The polarity of the energization that is applied to the control winding CW under these conditions causes the magnetic field of the wayside inductor to be "aiding" with respect to that of the train-carried receiver. Under these circumstances, a caution or intermediate speed control becomes effective on the train-carried equipment as it passes the wayside inductor.

The circuit for energizing the control winding is not completed until the approach relay 2A drops away and closes its back contact 81. At the same time, the dropping away of relay 2A opens its front contact 83 and causes the relay 2AP to become deenergized. Since a front contact 82 of the relay 2AP is included in the energizing circuit for the control winding CW, the dropping away of relay 2AP must be prevented if the control winding is to remain energized. Because of the relatively large inductance of the control winding CW, the current through it builds up fairly slowly after back contact 81 of relay 2A closes. The slow release characteristics for the relay 2AP, as designated by the heavy base line for the symbol of this relay, are chosen so that this relay will ordinarily not drop away during the time required for the current in the control winding to assume its normal value beginning with the time of closure of back contact 81. The normal current level in the energizing circuit for the control winding CW causes the relay 2CK to be picked up. If relay 2CK picks up before the relay 2AP can drop away, a stick circuit is completed for the relay 2AP which includes the front contact 84 of relay 2CK and front contact 85 of relay 2AP. The relay 2AP is then prevented from dropping away so that its front contact 82 remains closed and the control winding remains energized.

As a result of this circuit organization, the current level through the control winding of the inductor is required to remain above the drop away current level for the relay 2CK. Otherwise, the relay 2CK drops away and opens the stick circuit for the relay 2AP. If relay 2AP should drop away, it could not again be picked up because the presence of a train in the track section 1T causes the pick-up circuit for relay 2AP to remain open at front contact 83 of relay 2A. This circuit arrangement makes it impossible for the circuit to the control winding CW to remain closed in the event that the energization level to this winding drops below the required value. The reason for this precaution is that there otherwise would be substantially a short-circuit across the control winding in the event of failure of the power supply while the energizing circuit remained intact. It has been found that short-circuiting of the control winding of an inductor has the effect of making the wayside inductor substantially ineffective with respect to the train-carried receiver. A wayside inductor with a short-circuited control winding would, therefore, be incapable of inductively transmitting a re-

strictive influence to passing vehicles. The possibility of occurrence of such a dangerous situation is eliminated by this circuit arrangement which open circuits the control winding if the proper energization level for the winding 5 cannot be maintained. When so open-circuited, the wayside inductor is effective to provide the most restrictive control on train-carried apparatus as has already been described.

If neither track section 3T nor 2T is occupied, then both 10 track relays 3TR and 2TR are energized, and the respective relays 3HD and 2HD are also energized. With front contacts 76 and 77 of relay 3HD closed, the line wires 68 and 69 are energized with a polarity that causes the polar contacts 36 and 37 of relay 2HD to be in their right-hand positions. If a train then enters the track section 1T so that approach relay 2A is dropped away, a circuit is completed from (+), through back contact 78 of relay 2A, front contact 79 of relay 2HD, and right-hand contact 80 of relay 2HD, and the lamp G of wayside signal S2 to (-). Under these circumstances, a clear or proceed indication is displayed by the wayside signal 2.

Upon closure of back contact 81 of relay 2A, a circuit is again completed to energize the control winding CW of the wayside inductor IND at this location. This circuit 25 is similar to the one previously described except that it now includes the right-hand polar contacts 36 and 37 of relay 2HD so that the polarity of the energization is reversed. This polarity of energization causes the wayside inductor to have a magnetic field "opposing" that of the train-carried receiver. As already described, an "opposing" field causes a clearing influence to be inductively transmitted to the train-carried equipment of passing vehicles.

It is frequently desirable that an auxiliary wayside 30 inductor be located along the trackway some distance to the rear of each signal location. When a train occupies the track section 3T, for example, the wayside inductor IND at this signal location has its control winding CW open-circuited so that a vehicle passing this location receives the most restrictive control. If an auxiliary inductor such as the inductor 87 is not used, it is ordinarily necessary with a train occupying track section 3T also to open-circuit the control winding of the wayside inductor IND at the signal 2 location. The reason is that a train 35 occupying the track section 3T may actually be close to the signal S3 location. If the wayside inductor IND at the signal 2 location were controlled so as to inductively transfer only an intermediate speed control to vehicles entering the track section 2T, such vehicles would travel 40 through the track section 2T at what is still a fairly high speed. Although the engineer would receive a stop indication from the wayside signal S3, the train speed probably 45 could not be reduced sufficiently to avoid a serious collision with the preceding train just within the track section 50 3T with its rear cars still near the signal S3 location.

To avoid this situation without using an auxiliary inductor, it would be necessary to control the wayside inductors IND at both the signal S3 and S2 locations to inductively transfer the most restrictive control to passing 55 vehicles whenever the track section 3T is occupied. The difficulty arising from this solution is that a train occupying the section 3T but about to leave that section and move into the next section ahead would still cause the wayside inductor IND at the signal S2 location to be controlled so as to give the most restrictive control to passing vehicles. A vehicle entering the track section 2T would then be required to travel the entire length of this track section as well as track section 3T at a very slow speed even though the wayside signal S3 might change to a less 60 restrictive aspect shortly after the vehicle enters the track section 2T.

By using the auxiliary inductor 87 some distance to the 65 rear of each wayside signal location, these difficulties are alleviated. The wayside inductor 87 is shown as having its control winding CW selectively short-circuited or open-

circuited through the front contact 88 of the relay 3HD which is at the signal S3 location. This wayside inductor 87 is shown as being located at braking distance in advance of the signal S3 location; braking distance here meaning the distance required for the heaviest train to come to a stop from the intermediate speed.

When a train occupies the track section 3T, the relay 3HD is dropped away so that the control winding for the wayside inductor IND at the signal S3 location is open-circuited as already described. With relay 3HD dropped away, the polarity of the energization transmitted over line wires 68 and 69 to relay 2HD causes the control winding of the wayside inductor IND at the signal S2 location to be energized to give a caution or medium speed control.

A train approaching the signal S2 location at speeds above the medium speed limit is required to reduce its speed after it passes the inductor at this location or pay the penalty of an automatic application of the brakes. Assuming that the train speed is properly reduced, the train continues to move through the track section 2T at speeds below the medium speed limit until the vehicle-carried receiver passes over the wayside inductor 87. If the vehicle ahead has in the meanwhile moved out of the track section 3T, the track relay 3TR is picked up so that the relay 3HD is again energized. With front contact 88 of relay 3HD closed, the control winding CW for the wayside inductor 87 is short-circuited. The short-circuiting of this control winding causes the wayside inductor 87 to have substantially no effect upon the vehicle-carried apparatus. The vehicle can then proceed through the rest of the track section 2T at the medium speed limit. When the train passes the wayside inductor at the signal S3 location, either a clear or an intermediate control is transferred to the vehicle depending upon whether the train ahead is in the second or third block in advance.

Assume now that the vehicle enters the track section 2T while there is a vehicle occupying the track section 3T. The medium speed limit is again imposed upon the vehicle as the receiver passes over the wayside inductor at this signal S2 location. Upon reducing the train speed below this medium speed limit, the vehicle is allowed to travel through the track section 2T at speeds not exceeding the medium speed limit until the wayside inductor 87 is reached. If the vehicle ahead has in the meanwhile not moved out of the track section 3T, the track relay 3TR for that track section will still be dropped away. The relay 3HD will be dropped away also because of the open front contacts 71 and 72 of relay 3TR so that open front contact 88 of relay 3HD will cause the control winding for inductor 87 to be open-circuited. As the receiver passes over this wayside inductor 87, the most restrictive control will be inductively transferred to the vehicle-carried equipment. To avoid an automatic application of the brakes, the engineer is required to acknowledge the presence of this auxiliary inductor and to immediately reduce the train speed below the newly imposed lowest speed limit. Because this wayside inductor is located at braking distance ahead of the signal S3 location, the train speed can be reduced to the lowest speed limit by the time it arrives at the entrance to the track section 3T so that if the train ahead is occupying the track section 3T near the entrance end of this track section, the train to the rear can be stopped in time to avoid a collision.

The use of the auxiliary wayside inductor to the rear of the entrance to each track section provides for safe train operation in that it gives a forewarning if the track section ahead is occupied. At the same time, it makes it unnecessary for a train to operate at the lowest speed throughout an entire track section when the track section ahead may during a great portion of this interval be unoccupied. The marker signal M is located at the wayside near this auxiliary inductor as a warning to the engi-

neer of an approaching train travelling at restricted speeds that he is about to pass an inductor that may be open-circuited so that acknowledgement may be required.

Having described an intermittent inductive speed control system for railroads as a specific embodiment of this invention, we desire it to be understood that this form is selected to facilitate in the disclosure of this invention rather than to limit the number of forms it may assume. Also, various modifications, adaptations, and alterations may be applied to the specific form shown to meet the requirements of practice without in any manner departing from the spirit or scope of this invention.

What we claim is:

1. An intermittent inductive speed control system for railroads comprising, wayside apparatus including an inductor having a control winding, circuit means for selectively open-circuiting said winding or energizing said winding with one polarity or the other of direct current, train-carried apparatus including a receiver having both a primary and a single secondary winding inductively coupled together through a common magnetizable core structure, circuit means for energizing said primary winding to thereby magnetize said core structure, a circuit for said secondary winding comprising two series connected electro-magnetic relays and a source of direct current, said relays being constructed to operate in response to different levels of direct current, said source supplying a predetermined value of direct current to said series-connected relays to cause one of said relays to be normally picked up and the other of said relays to be normally dropped away, said receiver when passing through an inductive coupling relationship with said inductor having the current in its secondary winding selectively varied above and below said predetermined value depending upon whether said control winding is open-circuited or energized with said one or the other of said polarities of direct current to selectively drop away and pick up said one and said other of said relays respectively, and circuit means responsive to the conditions said relays are actuated to as said receiver and inductor pass through said coupling relationship to establish a speed limit for said train.
2. An intermittent inductive speed control system for railroads in which controlling influences are transferred from the wayside at fixed locations to passing trains through the inductive cooperation of wayside inductors and receivers associated with train-carried equipment comprising, said wayside inductor at each wayside location provided with a control winding and circuit means controlled in accordance with the controlling influence desired to become effective on passing vehicles for selectively open-circuiting said control winding or energizing said control winding with direct current of one polarity or the other, train-carried apparatus including said receiver being adapted to pass through an inductive coupling relationship with said inductor during train movement, said receiver having a magnetized core structure and a winding about said core structure, a receiver circuit including in series connection said winding and two electro-magnetic relays and a source of current for energizing said circuit, said energization of said receiver circuit being effective to cause one of said relays to be normally picked up and the other of said relays to be normally dropped away, the current in said receiver when said receiver and said inductor pass through said inductor coupling relationship being distinctively varied, said current being substantially only reduced to cause said first relay to drop away when said control winding is open-circuited, said current varying first above and then below its normal value to cause said second relay first to pick up and then said first relay to drop away when said control winding is energized with said one polarity of direct current, and said current varying first below and then above its normal value causing said first relay to drop away and then said second relay to pick up when said control winding is

energized with the opposite polarity of direct current, and circuit means responsive to the distinctive actuations of said two relays for effecting correspondingly different controls with respect to the speed of said train.

3. Train-carried apparatus for an intermittent inductive train control system wherein wayside inductors at fixed locations are provided with control winding selectively open-circuited or energized for distinctively different control influences comprising, a receiver having a magnetized core structure and a winding about said core and adapted to pass through an inductive coupling relationship with said inductor during train movement, relay circuit means including said receiver winding being differently responsive to distinctive current changes occurring in said receiver winding by inductive action according to whether said control winding is open-circuited or energized, a speed control relay and speed control means associated therewith for permitting maximum train speeds when said speed control relay is energized, a manually operable acknowledge contactor, circuit means responsive to a successively occurring current increase and decrease produced in said receiver winding in response to a clearing control influence for energizing said speed control relay provided said acknowledge contactor has been operated, stick circuit means for said speed control relay to maintain said relay energized between successive wayside inductor locations when once energized, circuit means including a penalty relay becoming deenergized in response to said current decrease unless said acknowledge contactor is actuated, circuit means responsive to an occurrence of said successively occurring current increase and decrease when said speed control relay is energized for preventing deenergization of said penalty relay even though said acknowledge contactor has not been operated, whereby said acknowledge contactor must be operated when the first clearing control influence is received but is not required to be operated when clearing controls after the first are being received.

4. Train-carried apparatus for an intermittent inductive train control system wherein wayside inductors at fixed locations are provided with control windings selectively open-circuited or energized for distinctively different control influences comprising, a receiver having a magnetized core structure and a winding about said core structure and adapted to pass through an inductive coupling relationship with said inductor during train movement, relay circuit means comprising said receiver winding being differently responsive to distinctive current changes occurring in said receiver winding by inductive action according to whether said control winding is open-circuited or energized, said distinctive current changes comprising substantially only a current decrease for a restrictive speed control and a current increase followed by a current decrease for a clearing speed control, a manually operable acknowledge contactor, said circuit means being effective in response to said current decrease to cause an automatic brake application unless said contactor is operated to acknowledge said restrictive control, circuit means including a speed control relay being actuated by said relay circuit means in response to a clearing speed control only provided said acknowledge contactor has been operated, stick circuit means to hold said speed control relay actuated between successive wayside inductor locations after receiving a clearing control and until a restrictive control is received, means governed by the actuated condition of the speed control relay and by the response of said relay circuit means to a current increase in said receiver winding for preventing a response of said relay circuit means to the immediately following current decrease, whereby said acknowledge contactor is required to be operated when the first clearing control influence is received but is not required to be operated when clearing controls after the first are being received.

5. In an intermittent inductive train control system, wayside apparatus including an inductor having a magnetizable core structure with a control winding about said

core, inductor control circuit means governed by wayside signalling apparatus for selectively energizing said core winding in accordance with distinctive control influences desired to become effective on passing vehicles, and relay circuit means responsive to the amplitude of current energizing said control winding and acting on said inductor control circuit means to open-circuit said control winding when said amplitude falls below a prescribed level.

6. In train-carried apparatus for an intermittent inductive train control system in which control windings of wayside inductors at fixed locations are selectively controlled to distinctively influence said train-carried apparatus through inductive action for correspondingly different train controls, a receiver having a magnetized core structure with a winding about said core structure, relay circuit means including said receiver winding being distinctively actuated momentarily by the respectively different current changes produced by inductive action in said secondary winding according to the control of said control winding, a plurality of electro-magnetic relays each having pick up windings adapted to be energized in response to a correspondingly distinctive actuation of said relay circuit means, a capacitor shunting said pick up winding of each of said relays to permit said relays to become picked up in response to the momentary actuation of said relay circuit means and auxiliary windings of each of said relays, circuit means associated with each relay and including a normally charged capacitor becoming effective in response to said actuation of said relay to energize said auxiliary winding to thereby maintain said associated relay picked up for a limited time.

7. An intermittent inductive speed control system for railroads comprising, wayside apparatus including an inductor having a control winding, circuit means for selectively open-circuiting said winding or energizing said winding with one polarity or the other of direct current, train-carried apparatus including a receiver having secondary and primary windings inductively coupled together through a common magnetized core structure, a circuit for said secondary winding comprising two electromagnetic relays connected in series with said winding, said receiver when passing through an inductive coupling relationship with said inductor having the current in its winding varied distinctively in both directions with respect to the normal current level in said winding depending upon whether said inductor control winding is energized with one or the other of said polarities of direct current to selectively actuate thereby both of said electromagnetic relays, said electromagnetic relays being both operated and in a distinctive sequence in accordance with the polarity of energization of said control winding, said current in said secondary winding varying substantially in only a single direction to cause only one of said electromagnetic relays to be operated when said receiver passes through an inductive coupling relationship with an inductor having its control winding open-circuited, and circuit means responsive to the selective sequential operations of said relays for establishing corresponding speed limits for said train.

8. In an intermittent inductive speed control system for railroads comprising, wayside apparatus including an inductor having a control winding, circuit means for selectively open-circuiting said winding or energizing said winding with one polarity or the other of direct current, train-carried apparatus including a receiver having secondary and primary windings inductively coupled together through a common magnetizable core structure, circuit means for energizing said primary winding to thereby magnetize said core structure, a positive responsive control relay and a negative responsive control relay connected in series with said secondary winding, circuit means for energizing said secondary winding and said relays with a normal current level to cause said positive responsive relay to be dropped away and said negative responsive relay to be picked up, said secondary winding experiencing

ing successive positive and negative current variations with respect to its said normal current level when said receiver passes said inductor having its control winding energized with direct current to thereby cause said relays to be sequentially operated, the sequence of operation of said positive and negative responsive relays independent of the polarity of energization of said control winding, said receiver secondary winding experiencing substantially only a negative current variation when said receiver passes an indicator having its control winding open-circuited to thereby cause only said negative responsive relay to be actuated, and circuit means responsive to the selective actuation of said electromagnetic relays for imposing different speed limits upon said vehicles.

9. Train-carried apparatus for an intermittent inductive train control system of the type wherein wayside inductors at fixed locations are each provided with a control winding selectively open-circuited or energized for distinctively different control influences comprising, a receiver on said train having a magnetized core structure and a winding about said core structure and adapted to pass through an inductive coupling relationship with said inductor during train movement, a positive responsive relay and a negative responsive relay being both connected in series with said winding, means for energizing said winding with direct current of a level to cause said positive responsive relay to be normally dropped away and said negative responsive relay to be normally picked up, said receiver winding experiencing distinctive current changes as said receiver passes an inductor having its control winding energized with direct current, said current in said winding increasing above its normal level to momentarily pick up said positive responsive relay and then decreasing below its normal level to drop away said negative responsive relay when said control winding is energized with one polarity of direct current, said current in said secondary winding first decreasing below its normal level to drop away said negative responsive relay and

then increasing above its normal level to pick up said positive responsive relay for the other polarity of direct current applied to said control winding, circuit means for restoring said negative responsive relay to its normal 5 picked up condition a predetermined interval after it has dropped away, a first speed control relay being picked up when said positive responsive relay is picked up provided that said negative responsive relay has not yet dropped away, a second speed control relay being picked up when said positive responsive relay is picked up provided that said negative responsive relay has previously dropped away, a repeater relay for each of said speed control relays for storing a received control received at one inductor location until said train reaches the next inductor location, stick circuit means for said repeater relays of said speed control relays for maintaining a repeater relay energized between successive inductor locations, means responsive to the dropping away of only said negative responsive relay when said receiver passes an inductor having its control winding open-circuited for interrupting said stick circuits to thereby cause said repeater relay for said speed control relays to be dropped away, and circuit means comprising a speed governor and said repeater relays of said speed control relays for imposing 10 preselected speed limits upon said train in accordance with the control then effective upon the control winding of each inductor.
